CLAIM

The ornamental design for a container scraper, as shown and described.

DESCRIPTION

FIG. 1 is a perspective view of a container scraper showing our new design;

FIG. 2 is a first side view thereof;

FIG. 3 is a second side view thereof;

FIG. 4 is a front view thereof;

FIG. 5 is a back view thereof;

FIG. 6 is a top view thereof; and,

FIG. 7 is a bottom view thereof.

The broken lines in the figures are included for the purpose of illustrating portions of a container scraper and form no part of the claimed design.

1 Claim, 3 Drawing Sheets# US D842,566 S
